UNITED STATES PATENT OFFICE.

EDMOND A. HUSEBY, OF CHICAGO, ILLINOIS.

TEMPO BOX.

Application filed May 15, 1926. Serial No. 109,294.

This invention relates to what are commonly known as tempo boxes constituting a part of the pneumatic actions of player pianos, and serving to regulate and control the speed at which the roll motor operates and the music sheet is drawn over the tracker bar during the playing; such tempo boxes commonly having associated therewith a valve for effecting the rapid rerolling of the sheet, and also a stabilizing device usually consisting of a valve in the suction passage from the roll motor to the vacuum chest or suction pump that is controlled by a pneumatic subjected on one side to spring action and on the opposite side to the vacuum existing in the tempo box, and operating to automatically neutralize the variations in the pressure existing in the system during the playing of a piece.

One object of my present invention is to provide a very simple, inexpensive and compact device for performing the above-noted functions. Other objects are to provide an improved automatic vacuum stabilizing device, including improved means for adjusting the sensitiveness and responsiveness thereof, to provide an improved throttle valve mechanism, and to provide an improved reroll valve. Other objects and attendant advantages of the invention will be apparent to persons skilled in the art as the same becomes better understood by reference to the following detailed description, taken in connection with the accompanying drawings wherein I have illustrated one practical and approved embodiment of the invention, and in which—

Fig. 1 is a vertical longitudinal section, taken on the line 1—1 of Fig. 2;

Fig. 2 is a horizontal section taken on the line 2—2 of Fig. 1;

Fig. 3 is a vertical longitudinal section through the bottom wall of the box taken on the line 3—3 of Fig. 2; and

Fig. 4 is a vertical transverse section taken on the line 4—4 of Fig. 2.

Referring to the drawings, the tempo box shown therein is a hollow rectangular wooden structure, comprising a relatively thick bottom wall 10, side walls 11, end walls 12, and a top wall or cover 13 detachably mounted on the upper edges of the side and end walls as by screws 14 and rendered air-tight by suitable gasket 15.

In and substantially centrally of the bottom wall 10 is formed a longitudinal duct

16 that at its inner end opens into the interior of the box through a port 17 and at its outer end communicates with an elbow nipple 18, which latter is connected by the usual rubber tubing to the vacuum chest in which a partial vacuum is constantly maintained through the action of exhausters or a suction pump. Surrounding the port 17 is an annular washer 19 of leather or like material constituting a valve seat.

In one side of the bottom wall 10, parallel with the duct 16, is formed a round bore 20 in which is tightly fitted a thin sheet-metal tube 21, one end of which projects through one of the end walls 12 in the form of a nipple 21', to which is connected a tube leading to the music roll motor.

In the upper portion of the bottom wall of the box directly over the hole 20 is formed an oblong slot 22; and the portion of the tube 21 registering with the slot 22 is cut out to form a widthwise tapered opening or port 23. Slidably fitting the tube 21 is a valve in the form of a solid plunger 24, adapted, by a sliding movement, to more or less throttle the port 23. Attached to one end of the plunger 24 is a rod or wire 25 that is connected at its other end to the usual tempo-regulating lever.

With the parts in the position shown, wherein the plunger valve is fully retracted, the tapered port 23 is wholly uncovered and the full strength of the suction is exerted through the nipple 18, duct 16, port 17, port 23, tube 21 and nipple 21' upon the music roll motor. When the plunger 24 is pushed inwardly to partially close the port 23, the flow passage is correspondingly throttled, and the speed of the music roll motor reduced, in a manner well understood in devices of this character.

The pressure stabilizing device in this case comprises a pneumatic within the tempo box, the movable side of which carries a valve that serves to more or less throttle the port 17. Heretofore, so far as I am aware, in pressure-stabilizing devices of this type the valve-carrying leaf of the pneumatic has been actuated in valve-closing direction by a spring, and in valve-opening direction by the suction existing within the box. My present invention reverses these opposing influences by an improved construction which also permits both a rough and a fine adjustment of the sensitiveness of the stabilizing pneumatic. Attached to the under side of

the cover-plate 13 is a tapered wooden block 26 forming the fixed side of the stabilizing pneumatic, to which is connected, through the usual bellows cloth, the hinged or movable side 27. Attached to and projecting forwardly of the swinging end of the side 27 is a finger 28 in which is anchored the lower end of a pull spring 29 that is housed in a tube 30 mounted in the cover-plate 13. The upper end of the spring 29 is attached to a cap screw 30' threaded through a tapped aperture in the upper end of the tube 30 and equipped with a lock nut 31 for securing it in set position. Manifestly, the pull of the spring 29 tends to maintain the stabilizing pneumatic in collapsed position against the opposing pull of the suction within the box, with a strength dependent upon the adjustment of the spring 29. On the under side of the movable leaf 27 of the pneumatic is mounted a valve, preferably taking the form of a felt disc 32 supplied with a lower facing 33 of leather; this valve manifestly acting to more or less throttle the port 17 accordingly as the stabilizing pneumatic is expanded by the vacuum or collapsed by the spring 29.

The spring 29 having been roughly adjusted to a strength adequate to afford approximately the normal or desired pressure in the vacuum chamber, the sensitiveness of the pneumatic may be more finely adjusted by the device shown in Fig. 1, comprising an atmospheric duct to the interior of the pneumatic that is controlled by a finely regulable device such as a needle valve. This device, in the form herein shown, consists of a short tube 34 mounted in the cover-plate 13 with its lower end in register with a hole 35 formed through the block 26 and opening into the interior of the pneumatic. The tube 34 is formed with an enlarged head 36 containing a valve seat 37, which latter in turn is more or less throttled by a needle valve 38 having screw-threaded engagement with the head 36 and secured in adjusted position by a lock nut 39. In opposite sides of the head 36 are holes 40 through which atmospheric air, in amounts permitted by adjustment of the needle valve, can flow into the interior of the pneumatic as the latter is expanded by the pull of the suction on its under side. Manifestly, when the vent duct last described is nearly throttled, the vacuum in the box works not merely against the pull of the spring 29 but against a partial vacuum within the pneumatic; whereas, when the vent duct is open sufficiently to freely admit atmospheric air to the interior of the pneumatic in response to the expanding movement of the latter, the vacuum in the box works only against the pull of the spring 29. By manipulating the needle valve 38 in or out, the effect of the spring 29 in opposing the vibrations of

the valve 33 may be increased or diminished without adjusting the tension of the spring 29 and to a finer extent than can be secured by such adjustment alone.

When the roll motor is reversed to rewind the music sheet, speed is desired, and hence it is common practice to provide a by-pass around the throttle and pressure-stabilizing valves of the box. My present invention provides a very simple and practical device for this purpose, consisting of a plate 41 pivoted to the bottom 10 of the box at 42 and overlying and normally covering a pair of transversely aligned ports 43 and 44 leading from the ducts 21 and 16 into the interior of the box. In the under side of the plate 41 is formed a channel 45 which is continuously in communication with the port 43 and normally out of communication with the port 44, but may be brought into communication with the latter so as to connect the two ports through the channel 45 by means of a pull rod 46 connected to one end of the reroll valve 41 and extending through one of the end walls 12 of the box and connected to either a manual or automatic actuating device.

Mounted in the bottom wall 10 of the box is a threaded rod 47 having on its upper end a felt-capped head 48 and on its lower end a knurled knob 49; this device constituting an adjustable stop to limit the expanding movement of the stabilizing pneumatic and prevent full closing of the port 17.

From the foregoing it will be seen that by my invention I have provided in small and compact compass a tempo-regulating mechanism manually or automatically actuated by the plunger valve 24; an automatic pressure-stabilizing device capable of fine regulation through manipulation of the needle valve 40; and a simple and easily manipulated reroll valve. The box may, of course, be mounted at any suitable or convenient place within the piano and readily connected up by lines of tubing to the music roll motor, the vacuum chest or suction pump, the tempo-regulating lever, and the reroll lever.

While I have herein shown and described one practical and simple embodiment of the invention, it is manifest that the structural details may be varied without departure from the operative principles involved or sacrifice of any of the inherent benefits and advantages. Hence, I reserve all such variations, modifications and mechanical equivalents as fall within the spirit and purview of the appended claims.

I claim—

1. In a tempo regulator of the type described, the combination of a box formed with top, side and end walls, and a relatively thick bottom wall formed with a pair of air ducts in and lengthwise of its bottom wall communicating with ports opening into

the interior of said box and with air conduits to a roll motor and a source of suction respectively, and a plunger valve slidable in one of said ducts across the port through 5 which said valve-containing duct communicates with the interior of said box.

2. In a tempo regulator of the type described, the combination of a box formed with top, side and end walls and a relatively 10 thick bottom wall, said bottom wall being formed with an air duct communicating at one end through a port with the interior of said box and at its other end with an air conduit to a source of suction, and with a 15 second air duct communicating at one end through a slot with the interior of said box and at its other end with an air conduit to a roll motor, a metal tube forming a lining for said second air duct and having an elongated opening registering with said slot, and a plunger valve slidable in said tube across the said opening.

3. In a tempo regulator of the type described, the combination of a box containing 25 a vacuum chamber and formed with air ducts in its bottom wall communicating with the ports opening into said vacuum chamber and with air conduits to a roll motor and a source of suction, a valve slidable in one 30 of said ducts across the port of said valve-containing duct, a pressure stabilizing pneumatic suspended from the top wall of said box, and a valve on the movable side of said pneumatic controlling the port of the other 35 of said ducts.

4. In a tempo regulator of the type described, the combination of a box containing a vacuum chamber and formed with ports 40 communicating with air conduits to a roll motor and a source of suction, a tempo-

regulating valve slidable across one of said ports, a pressure stabilizing pneumatic suspended from the top wall of said box, a throttle valve on the movable side of said pneumatic controlling the other of said 45 ports, a spring tending to collapse said pneumatic against the pull of the suction in said vacuum chamber and thereby open said throttle valve, and an atmospheric vent to the interior of said pneumatic. 50

5. A specific embodiment of claim 4, wherein said atmospheric vent to the interior of said pneumatic is equipped with a regulating valve adapted to more or less throttle the flow of air through said vent. 55

6. In a tempo regulator of the type described, the combination of a box containing a vacuum chamber and formed in its bottom wall with ports communicating with air conduits to a roll motor and a source of 60 suction, a tempo-regulating valve slidable across one of said ports, a pressure stabilizing pneumatic suspended from the top wall of said box, a throttle valve on the movable side of said pneumatic controlling the other 65 of said ports, a spring housing mounted on the top wall of said box, a pull spring connected at its lower end to said movable side of the pneumatic and at its upper end anchored in said casing, and an atmospheric 70 vent through said top wall to the interior of said pneumatic.

7. A specific embodiment of claim 6, wherein said pull spring is anchored in said 75 spring casing through the agency of an adjusting screw mounted in the top wall of the casing whereby the tension of the spring may be increased or reduced.
